RICHARD A. LEADBETTER, OF DETROIT, MICHIGAN, ASSIGNOR TO THE FARRAND COMPANY, OF DETROIT, MICHIGAN, A CORPORATION OF MICHIGAN.

EXPRESSION DEVICE FOR PNEUMATICALLY-OPERATED MUSICAL INSTRUMENTS.

1,103,213.

Specification of Letters Patent.

Patented July 14, 1914.

Application filed July 16, 1912. Serial No. 709,687.

To all whom it may concern:

Be it known that I, RICHARD A. LEADBETTER, a citizen of the United States of America, residing at Detroit, in the county 5 of Wayne and State of Michigan, have invented certain new and useful Improvements in Expression Devices for Pneumatically-Operated Musical Instruments, of which the following is a specification, reference being had therein to the accompanying drawings.

The invention relates to expression devices for pneumatically operated, self-playing musical instruments, being particularly 15 adapted for use in connection with percussion instruments, such as pianos.

Heretofore various devices have been employed for accentuating certain notes in the music, some of which have been operated by 20 the pumping pedal. Where however these accentuating devices are controlled solely by the pedal, they have failed to respond as quickly as is desirable for the proper accentuation of the music.

25 The present invention is designed to overcome this objection and consists first in the means employed for instantaneously changing the pneumatic pressure upon a proper manipulation of the pedal, and further in 30 the peculiar construction and arrangements of parts as hereinafter set forth.

In the drawings: Figure 1 is a cross section through the bellows and pumping pedal for a self-playing musical instrument, to 35 which my improvement is applied. Fig. 2 is a section through the communicating port at right angles to that shown in Fig. 1.

A is the storage-bellows; B the pumping-bellows; and C the actuating pedal for said 40 pumping bellows. The storage-bellows A is provided with suitable springs (not shown) for resisting the collapsing of the same, and which determines the normal pneumatic pressure at which the instrument 45 is operated, which pressure will gradually increase as the storage-bellows approaches a fully collapsed position. D is an inner bellows within the storage-bellows A, having its movable part D' in proximity to the 50 movable part A' of the outer bellows, with a bearing member E therebetween. The arrangement is such that the outer and inner bellows will normally move together and to permit of the equalization of the pneumatic 55 pressure within the outer and inner cham-

bers a normally open port F is arranged to connect the same.

Heretofore constructions as thus far described, have been employed in which the port F is restricted, so that when a sudden 60 stroke is given to the pedal the area of the port will be insufficient to equalize the pressure in the inner and outer chambers. This will cause the higher pneumatic pressure in the inner bellows to resist the collapsing of 65 the same and of the outer bellows, the effect being the same as increasing the tension of the resisting spring, and consequently increasing the power of the playing pneumatics. Such a construction will accentuate, 70 but experience has demonstrated that the accentuation is not as marked as is frequently desirable, and furthermore requires a very quick operation of the pedal to produce any effect. On the other hand if the 75 restriction of the port F is increased the response of the accentuating device will be easier, but there is then danger of accentuating where it is not desired. With my improved construction I have avoided this difficulty; first, by providing a port F of sufficient area to quickly and freely equalize the pressure within the inner and outer chambers under normal conditions, and, second, by providing a valve for completely closing 80 this port, which is actuated by a sudden stroke of the pedal and when closed will instantaneously raise the pneumatic pressure. By such a construction it is possible to accentuate an individual note in a manner that 85 cannot be accomplished by the continuously open restricted port. It also avoids danger of accentuating where not desired, and without regard to the number of pneumatics that are simultaneously under operation. 95

In the specific construction shown, G is the valve for closing the port F, which is arranged in a suitable housing H below the bar I in which the port F is formed, the port F comprising two bores F' and F² both communicating with the chamber within the housing H and one bore communicating with a space within the inner bellows D, while the outer bore is in communication with the chamber in the outer bellows outside of the 100 inner bellows. The valve G normally rests upon the bottom of the housing H and will permit the air to flow unobstructedly through the ports between the inner and outer bellows. When however a sudden impulse is 105 110

given to the pedal the increased velocity of air passing through the ports F' and the lateral port within the housing H will create a suction which will actuate the valve G, raising it to its seat and stopping further flow through the ports. As soon as the pressure is equalized which occurs quickly by the exhausting action of the playing pneumatics, the valve G will drop from its seat, again opening the ports and permitting a free flow of air therethrough.

To render the action of the valve H more positive and to prevent danger of its adhering to its seat, a light spring J is connected thereto, through the medium of a stem K.

What I claim as my invention is:

1. An expression device for pneumatically operated self playing musical instruments including a storage-bellows, a bellows within said storage-bellows collapsible therewith, means for actuating the bellows, the chambers within and without said inner bellows being normally in communication, and means controlled by the bellows actuating means for cutting off communication between said chambers.

2. An expression device for pneumatically operated musical instruments, comprising a storage-bellows, a bellows within said storage-bellows collapsible and expandable therewith and having an air passage normally establishing free communication between the spaces within the outer and inner bellows, bellows actuating means which when operated force air through said air passage, and means controlling the passage of air through said passage and acting to close the passage when air under excessive pressure is introduced in the passage.

3. An expression device for pneumatically operated musical instruments, comprising a

storage-bellows, an inner bellows collapsible and expandable with said storage-bellows a bar forming a common portion of the inner and outer bellows, said bar being provided with a port to establish communication between the chambers therein, said portion having a laterally extending housing, a valve arranged in the laterally extending housing and normally open, and means for forcing air through the port to actuate the bellows, said valve being actuated when the pressure of air is suddenly increased to close said port whereby communication between the chambers is checked.

4. An expression device for pneumatically operated musical instruments, comprising a storage-bellows, a bellows within said storage-bellows, collapsible and expandable therewith, a bar forming a common member of the outer and inner bellows ported for communicating respectively therewith, a recessed casing communicating with both of said ports, and a valve within said casing adapted to seat to close the port communicating with the outer bellows, but normally separated from its seat.

5. An expression device for pneumatically operated musical instruments, comprising a storage-bellows, a pneumatic resistor for increasing the tension of said storage-bellows, provided with a normally open port for throwing it out of action, a pump for exhausting said storage-bellows, and a valve responding to a sudden impulse of said pump for closing said port, and throwing said pneumatic resistor into action.

In testimony whereof I affix my signature in presence of two witnesses.

RICHARD A. LEADBETER.
